THERMOMETER FOR AN AUTOMOBILE VISOR OR THE LIKE

Albert Vinton Stegeman, Fort Thomas, Ky. (% Stegeman Products Incorporated, 18 E. Sixth St., Newport, Ky.)

Filed Mar. 1, 1961, Ser. No. 64,115

Term of patent 14 years

(Cl. D52—7)

FIG. 1 is a plan view of a thermometer for an automobile visor or the like, embodying my new design, shown in a flat position;

FIG. 2 is a view in front elevation thereof in operative position;

FIG. 3 is a view in side elevation thereof in operative position, and,

FIG. 4 is a plan view thereof in operative position.

The visor shown in broken lines in FIGS. 3 and 4 is included for purposes of illustration only.

I claim:

The ornamental design for a thermometer for an automobile visor or the like, as shown and described.
